CLAIM

The ornamental design for a vibrating handle with skin care attachment, as shown and described.

DESCRIPTION

FIG. 1 is a bottom plan view of a vibrating handle with skin care attachment showing my new design; and, FIG. 2 a top right side perspective view; the left side perspective view is a mirror image thereof.

The broken lines shown in the figures are for the purpose of illustrating portions of the vibrating handle with skin care attachment, which form no part of the claimed design.
